GARMENT

William Caplin, New York, N. Y., assignor to
Seamprufe Incorporated, New York, N. Y., a
corporation of New York

Application May 9, 1946, Serial No. 668,343

4 Claims. (Cl. 2-73).

1

This invention relates to garments, and particularly to substantially form-fitting ladies' garments, such as slips, nightgowns and the like.

A number of structures for garments of this class have been developed in the art in an attempt to achieve certain broadly desirable features, such as a snug fit, a smooth hang, substantial elasticity for applying and removing the garment, the lack of any tendency to sag, an attractive seam pattern, simplicity and economy of manufacture, adaptability to different figures and styles, and in general durable sales appeal.

In the absence in the garment of any materials other than the usual woven fabrics, and of any special fastenings or other complicated accessories, which play no part in this invention, there are certain definite main factors which together determine the behaviour of articles of this class, to wit: The number and shape of the component parts; the cut, that is, the direction of the threads of the goods in relation first to the direction of the main elastic stresses in the goods, and secondly to that of the seams; and the geometric pattern formed by the seams.

Certain consideration should be offered here to bring into sharp focus the nature of the invention, its objects, and the mode of its operation. The cut of a piece (bias or straight) determines whether the piece behaves as a substantially elastic one or not. The elasticity of a bias-cut piece, however, can be hindered or even nullified by an improperly positioned seam. It is also well known in the art that, when bias-cut pieces are properly joined to straight-cut pieces, not only do they display their fullest elasticity, but also they form seams which will not rip.

The loads on a garment of this class fall into three main categories: Vertical loads, due to the weight of the fabric; circumferential loads, due to the stretching of the fabric in places to conform closely to the outline of the body; and mixed loads, which arise from the wearer's sitting, bending and in general assuming positions different from the standing. All of these loads produce stresses which are transmitted partially unchanged through the straight-cut panels, induce deformations in the bias-cut panels, which deformations in turn generate secondary stresses, and finally run along the seams balancing each other at the nodal points or points of junction of several seams, according to the laws of vectorial composition.

Whether those elastic stresses act to improve or mar the fit and appearance of the garment,

2

depends on the structure of this latter, and precisely on the three main factors defined hereinbefore. Many efforts have been made along these lines in the prior art, but they have achieved at best only partial success. My invention, however, provides a garment structure wherein loads and stresses are so manipulated and channelled as to achieve the maximum beneficial effect thereof. The result is a garment simple and economical but more attractive, comfortable, and durable than any hitherto known.

It is the general object of this invention to provide a garment of the character described which has an improved fit and is especially flattering to the figure of the wearer.

It is also an object of this invention to provide a garment of the character described, wherein the fit is obtained through a novel and improved distribution of the stresses and deformations among the various component pieces, said stresses and deformation being transmitted through the suitably inter-related elements of a web of seams.

Other related and ancillary objects of my invention will clearly appear as the description proceeds.

In the drawings:

Fig. 1 is a front view of a garment according to the invention in position on the body of a wearer, said body being only schematically indicated.

Fig. 2 is a rear view of the same garment.

Fig. 3 is a front view of a fragment of the garment illustrating an alternate embodiment.

Fig. 4 is a plan view of the various component pieces of the garment, cut but not assembled.

Referring now in detail to the drawings, my improved garment, which in the preferred embodiment herein illustrated is a slip, comprises a skirt formed of a sector 1 disposed to the rear and sides and a front panel 2. The sector 1 is cut on the straight of the goods, which means that a set of threads runs parallel to its axis of symmetry. Obviously the edges of the sector are at an angle to the threads, as plainly illustrated in Fig. 3. Thus, when the sector 1 is draped on the person of the wearer, it can be said that it has some degree of bias in the portions thereof adjoining the front panel 2. The two pieces are joined along substantially vertical seams 3. The front panel 2 is cut on the bias. The top edge thereof is substantially shaped like an inverted V, the sides of which are preferably slightly convex towards the

bottom, and is joined to form the seam 4 with the lower edge, complementarily shaped, of a bias-cut midriff panel 5. The upper edge of the midriff panel is generally parallel to its lower edge but the sides thereof have a somewhat more pronounced convexity to provide a sharper upwardly extending vertex 6. Said upper edge of the midriff panel is connected with two breast cups 7 to form an inverted V seam 8. The two breast cups are also bias-cut and suitably tucked. From the vertex of the midriff panel, the hem 9 of each breast cup is shaped similarly to an inverted V, to the apex of which there is attached a shoulder strap 18.

The slip is completed by upper back panel 10, which is bias-cut. The lower edge of said panel 10 is shaped like a very flat V having sides convex towards the top and sharply curved in the vicinity of the apex 17 thereof. Said edge is joined to a complementarily shaped upper edge of the sector 1 to form a seam 11. The seam 11 is joined at both its ends and merges with the seam 4, so that these two seams may be looked upon as a continuation of one another. Further, the upper back panel 10 is joined to the midriff panel 5 to form short substantially vertical seams 12, and to the breast cups 7 to form short substantially vertical seams 13 and slanted seams 14. Substantially vertical seams 12 and 13 are aligned with one another and with substantially vertical seams 3. The upper edge or hem 15 of panel 10 has a shape commonly known as "gull wing," having two upwardly pointing apices 16 to which there are attached the shoulder straps 18, and a downwardly pointing apex 24 in the vicinity of which said hem 15 is substantially parallel to the portion of the seam 11 adjacent the apex of this latter. A gull-wing strip 19 may be attached on the inside of the garment to the top of the upper rear panel 10, and stitched thereto along a seam 23. Another piece 22 may, if so desired, be attached on the inside of the garment to the top of the front thereof.

The weight of the sector 1 is applied to the seam 11. Part of it is transmitted to the body of the upper back panel 10 and thence to the upper edge 15 thereof. The shape of this upper edge is such that any stresses along it result in vertical pull on the shoulder straps 18. Another portion of the weight of the skirt is transmitted by the seam 11 to the seam 4, and tends to spread out the inverted V-shaped midriff section. However the upper apex of said section is joined through the hems 9 of the breast cups to the shoulder straps, and therefore cannot yield. As a result the midriff panel is pressed against the body, thus dividing, shaping and contouring the breasts of the wearer and giving an uplift effect.

The weight of the front panel is applied to the seam 4, and transmitted through the midriff panel, and the hems 9 to the shoulder straps, substantially in the manner set forth in the above paragraph, achieving the same effect above described.

Circumferential stresses are generated in the following component pieces: the front panel 2, the midriff panel 5, and the upper back panel 10. The first two will stretch to allow the garment to be put on or taken off. During actual wear, and as long as the wearer is in a standing position, circumferential stress is predominantly concentrated in the upper back panel 10. Therefrom it is transmitted to the seams 12, tending to spread the midriff panel apart, and, as a consequence, pressing said midriff panel firmly against the

body to give the brassière effect already explained.

The same general results could be achieved with somewhat different constructions, for instance, as shown in Fig. 3, by having a midriff panel with a vertex 20 lower than the hems of the breast cups, and the two breast cups joined together above said vertex by way of a short vertical seam 21. Or a dart could be employed in place of the last mentioned seam. All that is necessary is that a continuous stitch line, capable of transmitting stresses in a relatively non-elastic manner, run from the vertex 6 to each front point of attachment of the shoulder straps, and said stitch line may comprise seams, reinforcements, darts, hems, or the like, or any combination thereof. Therefore the expression "a continuous stitch line" is to be given the construction herein set forth, whenever it occurs in the claims.

Circumferential stress in the upper portion of the upper back panel is directly communicated to the breast cups through the seams 13 and 14. The seams 13 bordering the bottom portions of the breast cups tend to be spread apart by said circumferential stress and therefore hold the bottom portions of the breast cups firmly against the body much in the same way in which the midriff panel is held. The seams 14 on the contrary are at a slant, following substantially the lateral contour of the breasts. Therefore they afford peripheral support to these latter under the action of circumferential stress. Meanwhile, the shape and tucking of the breast cups allow freedom and comfort in containing the breasts.

From the above analysis, an important feature of my invention clearly appears, to wit the manner in which vertical and circumferential loads are decomposed and guided by the seams of the garment until they cooperate to generate similarly directed stresses, in spite of the fact that originally such loads are at a right angle to each other. Of course the same will hold true in the case of any mixed loads that may arise, which can only be combinations of vertical and circumferential loads. It is to be noted particularly how downward pulls are made to help support and uplift the breasts, instead of having the contrary effect which would naturally be expected of them. Particularly the combination of the seams 4, 8, 12, 13, and 14 serves to guard the breast cups, and diverts and transforms any mechanical action that might tend to be harmful to them. In the front, where the shaping and form-fitting action of the slip is most important and most difficult to achieve, a continuous network of seams and hems runs from the bottom of the skirt to the shoulder straps, and prevents any downward pull from being transmitted substantially through the body of any piece in the upper part of the slip.

It will also be apparent to a person skilled in the art that the combination of straight and bias-cut pieces in the skirt provides the desired circumferential elasticity without sagging. The seams of the bias-cut panel 2 with the slightly biased edge portion of the straight-cut sector 1 are stable and rip-proof, and inasmuch as the sector 1 will not sag or ride, neither will the panel 2 so joined thereto.

While I have described a preferred embodiment of my invention in order to illustrate the same, I want it understood that I am not to be limited to the details herein set forth, inasmuch as many changes and modifications may be made therein as regards the type of garment, as well

as the style, proportions, and tailoring, and the details of construction thereof in general, without departing from the spirit of the invention or exceeding the scope of the claims.

I claim:

1. In a lady's garment, the combination of a straight-cut rear skirt panel having upwardly converging side edges, a lower arcuate connecting edge and an upper connecting edge having a centrally located downwardly extending inverted V depression, a bias cut front skirt panel having vertical side edges, a lower arcuate connecting edge and an upper connecting edge having a centrally located upwardly extending inverted V projection, said rear and front skirt panels being joined at seams extending along the side edges of each thereof to provide an enveloping skirt portion for the garment, a bias cut midriff panel having vertical side edges and shaped substantially like an inverted V joined at its lower edge to the upper edge of the front skirt panel, a front waist portion comprising a pair of breast cups, the adjacent lower edges of each of which are shaped substantially to form a downwardly extending substantially V-contoured depression, the respective inner slopes of the lower edge portions of said breast cups being complementary to the respective slopes of the upper edge of the midriff panel and joined thereto at seams extending along the same, a bias cut upper back panel having a lower edge complementary to the upper edge of the rear skirt panel and joined thereto along a seam extending along the same, the last-named seam being connected and merging at each end thereof with an end of the seam joining the midriff panel to the front skirt panel, said upper back panel being joined at seams to said midriff panel along the conjoint edges of each thereof, said last-named seams merging and being aligned with the seams connecting the sides of the front and rear skirt panels, and means for supporting the garment on the wearer.

2. In a lady's garment, the combination of a straight-cut rear skirt panel having upwardly converging side edges, a lower arcuate connecting edge and an upper connecting edge having a centrally located downwardly extending inverted V depression, a bias cut front skirt panel having vertical side edges, a lower arcuate connecting edge and an upper connecting edge having a centrally located upwardly extending inverted V projection, said rear and front skirt panels being joined at seams extending along the side edges of each thereof to provide an enveloping skirt portion for the garment, a bias cut midriff panel having vertical side edges and shaped substantially like an inverted V joined at its lower edge to the upper edge of the front skirt panel, a front waist portion comprising a pair of breast cups, the adjacent lower edges of each of which are shaped substantially to form a downwardly extending substantially V-contoured depression, the respective inner slopes of the lower edge portions of said breast cups being complementary to the respective slopes of the upper edge of the midriff panel and joined thereto at seams extending along the same, a bias cut upper back panel having a lower edge complementary to the upper edge of the rear skirt panel and joined thereto along a seam extending along the same, the last-named seam being connected and merging at each end thereof with an end of the seam joining the midriff panel to the front skirt panel, said upper back panel being joined at seams to said midriff panel along the conjoint edges of each thereof, said last-

named seams merging and being aligned with the seams connecting the sides of the front and rear skirt panels, the upper edge of the upper back panel having a centrally located downwardly extending V depression and having wings at its free end extremities sloping downwardly from an apex, said upper back panel wings being complementary to the other lower edge portions of the breast cups, and means for supporting the garment on the wearer.

3. In a lady's garment, the combination of a straight-cut rear skirt panel having upwardly converging side edges, a lower arcuate connecting edge and an upper connecting edge having a centrally located downwardly extending V depression, a bias cut front skirt panel having vertical side edges, a lower arcuate connecting edge and an upper connecting edge having a centrally located upwardly extending inverted V projection,

10 said rear and front skirt panels being joined at seams extending along the side edges of each thereof to provide an enveloping skirt portion for the garment, a bias cut midriff panel having vertical side edges and shaped substantially like an inverted V joined at its lower edge to the upper edge of the front skirt panel, a front waist portion comprising a pair of breast cups, the adjacent lower edges of each of which are shaped substantially to form a downwardly extending substantially V-contoured depression, the respective inner slopes of the lower edge portions of said breast cups being complementary to the respective slopes of the upper edge of the midriff panel and joined thereto at seams extending

20 along the same, a bias cut upper back panel having a lower edge complementary to the upper edge of the rear skirt panel and joined thereto along a seam extending along the same, the last-named seam being connected and merging at each end thereof with an end of the seam joining the midriff panel to the front skirt panel, said upper back panel being joined at seams to said midriff panel along the conjoint edges of each thereof, said last-named seams merging and being aligned

25 with the seams connecting the sides of the front and rear skirt panels, the upper edge of the upper back panel having a pair of apices, each breast cup having an apex, and shoulder straps connecting one apex of the upper back panel with one apex of a breast cup, and a continuous stitch line joining the upper vertex of said midriff panel to the points of attachment of the respective shoulder straps to the breast cups.

4. In a lady's garment, the combination of a straight-cut rear skirt panel having upwardly converging side edges, a lower arcuate connecting edge and an upper connecting edge having a centrally located downwardly extending V depression, a bias cut front skirt panel having vertical side edges, a lower arcuate connecting edge and an upper connecting edge having a centrally located upwardly extending inverted V projection,

30 said rear and front skirt panels being joined at seams extending along the side edges of each thereof to provide an enveloping skirt portion for the garment, a bias cut midriff panel having vertical side edges and shaped substantially like an inverted V joined to said front skirt panel and the lower inner edge of each breast cup at seams extending along the conjoint edges of each thereof, a bias cut upper back panel, the lower edge of which is complementary with the upper edge of

35 the rear skirt panel joined to the same along a

40 side edges, a lower arcuate connecting edge and an upper connecting edge having a centrally located upwardly extending inverted V projection, said rear and front skirt panels being joined at seams extending along the side edges of each thereof to provide an enveloping skirt portion for the garment, a bias cut midriff panel having vertical side edges and shaped substantially like an inverted V joined to said front skirt panel and the lower inner edge of each breast cup at seams extending along the conjoint edges of each thereof, a bias cut upper back panel, the lower edge of which is complementary with the upper edge of

45 the rear skirt panel joined to the same along a

50 side edges, a lower arcuate connecting edge and an upper connecting edge having a centrally located upwardly extending inverted V projection, said rear and front skirt panels being joined at seams extending along the side edges of each thereof to provide an enveloping skirt portion for the garment, a bias cut midriff panel having vertical side edges and shaped substantially like an inverted V joined to said front skirt panel and the lower inner edge of each breast cup at seams extending along the conjoint edges of each thereof, a bias cut upper back panel, the lower edge of which is complementary with the upper edge of

55 the rear skirt panel joined to the same along a

seam at the conjoint edges of each thereof and being connected and merging at each end thereof with an end of the seam joining said midriff panel to said front panel, said upper back panel being joined to said midriff panel at the side edges of each thereof along substantially vertical seams aligned with the seams joining the front panel to the rear skirt panel, said upper back panel being further joined at a seam along its sides to a section of each of the lower outer edges of the breast cups at conjoint edges of each thereof, which seam is substantially vertical and aligned with one of the seams joining said upper back panel to said midriff panel and along its upper edge to the remaining section of each of the lower outer edges of the breast cups, said upper back panel having its upper edge shaped to provide two vertices forming the back points of attachment at said shoulder straps and said breast cups having respectively, at their upper edges, vertices forming the further points of attachment of said

shoulder straps, and a continuous stitch line joining the upper vertex of said midriff panel to each of the points of attachment of the shoulder straps to the breast cups and thereby to the rest of the garment.

WILLIAM CAPLIN.
